(57) **CLAIM**

The ornamental design for an motor vehicle and toy replica thereof, as shown and described.

DESCRIPTION

FIG. 1 is a right-front, perspective view of a motor vehicle and toy replica thereof of our new design, the left-front perspective view being a mirror image thereof, with the exception of the windshield wiper assemblies which are not symmetric, and the door over the gas cap, which is not present on the left side;

FIG. 2 is a right-rear, perspective view thereof, the left-rear, perspective view being a mirror image thereof, with the exception of the windshield wiper assembly which is not symmetric, and the door over the gas cap, which is not present on the left side;

FIG. 3 is a right-side view of thereof, the left-side view being a mirror image thereof, with the exception of the windshield wiper assemblies which are not symmetric, and the door over the gas cap, which is not present on the left side;

FIG. 4 is a front view thereof;

FIG. 5 is a rear view thereof; and,

FIG. 6 is a top view thereof.

As used herein right and left refer to the orientation of the design depicted in the figures above, not the right and left sides of the vehicle depicted.
